Attorney.

UNITED STATES PATENT OFFICE.

ARTHUR BOOZER, OF PROVIDENCE, RHODE ISLAND, ASSIGNOR TO TILLOTSON HUMIDIFIER COMPANY, OF PROVIDENCE, RHODE ISLAND, A CORPORATION OF RHODE ISLAND.

STEAM-TRAP.

1,200,161.

Specification of Letters Patent.

Patented Oct. 3, 1916.

Application filed March 31, 1913. Serial No. 757,745.

To all whom it may concern:

Be it known that I, ARTHUR BOOZER, of the city and county of Providence and State of Rhode Island, have invented certain new and useful Improvements in Steam-Traps; and I do hereby declare the following specification, taken in connection with the accompanying drawings, forming a part of the same, to be a full, clear, and exact description thereof.

The invention relates to steam traps and has for its object to simplify and improve the construction whereby the efficiency of the operation will be greatly increased.

To these ends the invention consists in the novel arrangement and combination of parts hereinafter described and more particularly set forth in the claims.

In describing the invention in detail reference will be made to the accompanying drawings, in which—

Figure 1 is a central longitudinal sectional elevation of my novel form of steam trap, the valve operating mechanism being shown in full lines in the position which it occupies when the valve is closed and in dotted lines when the valve is open. Fig. 2 is a plan view in section on line $x-x$, Fig. 1. Fig. 3 is a transverse section on an enlarged scale on line $y-y$, Fig. 1.

Referring to the drawings, 1 represents an egg-shaped shell or casing which is provided upon the side adjacent the bottom with a horizontally extending neck portion 1' and upon the opposite side adjacent the top with an inlet-pipe 2 through which the steam or water of condensation may enter the trap. The neck portion 1' is provided with a cover-plate 3 which is bolted to the casing and is provided with a screw-threaded opening 4 extending through the same. Mounted in the outer end of the opening 4 is an outlet-pipe 5 and screwed into the inner end of said opening is a rectangular hollow frame or support 6 having end walls 7 and 8, a partition wall 9 arranged between and parallel with said end walls and an externally threaded neck portion 10 formed integral with the end wall 8. The partition wall 9 divides the frame 6 into two compartments 11 and 12. The compartment 11 is open at the top and bottom and provided with a longitudinal slot 13 in each side, and the compartment 12 is

closed at the top and bottom and provided with an opening 14 in each side.

Removably mounted in the neck portion 10 and extending through the same is a hollow conical valve-seat 15, and mounted to slide in the walls 7 and 9 is a valve-stem 16 provided at each end with a conical valve 17. Said valve-stem 16 is also provided with a pin 18 extending radially through the central portion of the same and having the ends project through the slots 13 in the sides of the frame 6. Said pin 18 has a loose fit in the valve-stem 16 and is provided at each end with a thumb-nut 19 for holding the same in position.

A pair of parallel arms 20 are pivoted at their lower ends upon a pin 21 secured in ears 22 upon the bottom of the frame 6 and have their upper ends joined together by a pin 23. Said arms 20 are each provided with a longitudinal slot 24 through which the pin 18 extends. A float-lever 25 is provided at its free end with a hollow float 26 and is pivoted at the opposite end upon a pin 27 secured in ears 28 upon the top of the frame 6, said pin 27 being arranged in vertical alinement and parallel with the pin 21. Said float-lever 25 is provided at its pivoted end with a downwardly extending lateral projection 29 which is provided at its free end with a longitudinal recess 30 or slot 30. Said projection 29 is arranged and adapted to extend between the arms 20, so that the pin 23 will engage the recess 30 in said projection, as shown in Fig. 1.

The casing 1 is provided at the bottom with a screw-plug 31, which may be removed when it is desired to remove any sediment that may have accumulated in the bottom of the trap.

The operation of the device is as follows: The parts are normally in the position shown in full lines in Fig. 1, with the valve 17 in closed position. As the water of condensation begins to rise in the casing 1 the float 26 likewise rises and moves the float-lever 25 upon its pivot, thereby moving the projection 29 and the upper ends of the arms 20 to the left in Fig. 1. As the arms 20 are rocked to the left the pin 18 which engages the slots 24 will likewise be moved to the left in slots 13, thereby moving the valve-stem 16 to the left and opening the valve 17. When the water of condensation has passed out

through the outlet-pipe 5 the float 26 will fall, thereby moving the projection 29, arms 20, and valve-stem 16 to the right and closing the valve 17.

5 With the above construction it will be seen that the means for moving the valve-stem engage said stem at its center and between its two supporting walls, and there is less liability of any cramping or bending 10 of said valve-stem or uneven wearing of its bearings. It will likewise be seen that by removing one of the nuts 19 the pin 18 can be removed and the valve-stem 16 reversed so as to bring the other valve 17 in operative 15 position with the valve-seat 15. It will also be seen that by locating the neck portion of the casing above the bottom of said casing and by closing the bottom and top of the compartment 12 there is less liability of any 20 sediment entering said compartment and collecting upon the valve or valve-seat.

What I claim as my invention and desire to secure by Letters Patent is:

1. An article of the character described 25 comprising a suitable casing having an inlet and outlet, an outlet-valve seat, an outlet valve, a pivoted float-lever provided with a slot, a float connected to said float-lever, and an arm pivoted at one end to a fixed support 30 and provided at its opposite end with means for engaging said slot, said outlet-valve being provided with a pin in pivotal engagement with said arm intermediate its ends.

2. An article of the character described 35 comprising a suitable casing having an inlet and outlet, an outlet valve seat, an outlet valve having a stem slidably mounted, a pivoted float lever provided with a slot, a float connected to said float lever, and an 40 arm pivoted at one end to a fixed support and provided at its opposite end with means for engaging said slot, said outlet-valve stem being provided midway its length with a pin in pivotal engagement with said arm 45 intermediate its ends.

3. An article of the character described comprising a suitable casing having an inlet and outlet, an outlet valve seat, an outlet valve having a stem, a support for said 50 valve stem, a float-lever pivotally mounted on said support and provided with a slot, two parallel arms pivoted at one end to a fixed support and joined together at the opposite end by a pin arranged to engage said slot, a longitudinal slot in each arm between the ends thereof, and a pin loosely mounted in the center of said valve-stem arranged to engage said longitudinal slots.

4. An article of the character described 60 comprising a suitable casing having an inlet

and outlet, a frame mounted in said outlet, an outlet valve having a stem slidably arranged in said frame, a pin extending transversely through the center of said valve-stem, a float-lever pivotally mounted on said 65 frame and provided at one end with a float and at the opposite end with a lateral projection having a slot, two parallel arms loosely mounted at one end upon a pin secured in said frame and joined together at the opposite end by a pin arranged to engage said slot, and a longitudinal slot in each arm intermediate the ends thereof arranged and adapted to be engaged by the transverse pin in the valve-stem. 75

5. An article of the character described comprising a suitable casing having an inlet and outlet, a frame mounted in said outlet having end walls, an intermediate partition wall, and a longitudinal slot in each side 80 wall between said partition wall and the inner end wall, an outlet-valve having a stem slidably mounted in said partition wall and said inner end wall, a valve-seat in the outer end wall, a transverse pin loosely mounted in the center of said valve-stem and having the ends thereof engage the longitudinal slots in the side walls of the frame, two parallel arms loosely mounted at one end upon a pin secured in the side walls 90 of said frame and joined together by a pin secured in the opposite ends, a longitudinal slot in each arm intermediate the ends arranged to be engaged by the transverse pin in the valve-stem, a float-lever pivoted upon 95 a pin secured in said frame, a float upon one end of said float-lever, and a lateral projection upon said float-lever having a slot arranged to be engaged by the pin connecting the free ends of the parallel arms. 100

6. An article of the character described comprising a suitable casing having an inlet and outlet, a fixed support comprising a hollow rectangular frame divided by a transverse partition wall into two compartments, one of said compartments having the top and bottom open and the sides closed, and a valve-stem mounted to slide therein, the other of said compartments having the top and bottom closed, and an opening in 110 each side and a valve and valve-seat therein, a float-lever pivoted to said frame and provided with a float at one end and a pivoted arm connecting said float-lever with said valve-stem. 105
